UNITED STATES PATENT OFFICE.

JOSEPH L. WELLS, OF PHILADELPHIA, PENNSYLVANIA, ASSIGNOR TO THE
WESTON & WELLS MANUFACTURING COMPANY, OF CAMDEN, N. J.

BUSTLE.

SPECIFICATION forming part of Letters Patent No. 358,712, dated March 1, 1887.

Application filed November 8, 1886. Serial No. 218,318. (No model.)

To all whom it may concern:

Be it known that I, JOSEPH L. WELLS, a citizen of the United States, residing at Philadelphia, in the county of Philadelphia and 5 State of Pennsylvania, have invented certain new and useful Improvements in Bustles; and I do hereby declare the following to be a full, clear, and exact description of the invention, reference being had to the accompanying drawing, which forms part of this specification, in 10 which the figure is a perspective, partly broken away, of a bustle with my improvements applied thereto.

My invention has reference to bustles, and 15 has for its object to provide a covering for the same, which will serve to protect garments worn adjacent to the bustle from being soiled by contact with the latter, said covering being elastic, so as to contract and expand 20 with the bustle, and open, so as not to interfere with the free circulation of air through the latter.

My invention consists in the combination, 25 with the body of a bustle made of braided material, of a braided, knitted, or open-work textile covering therefor, constructed and applied substantially as hereinafter set forth.

Referring to the accompanying drawing, A represents a bustle, the body of which, B, is 30 shown as composed of braided wire, and which has a waistband, C.

The braided wire composing the body of the bustle is liable to soil garments with which it may contact, and particularly white garments 35 constituting underwear. To prevent such soiling I provide the body B with a covering, D. Said covering is of textile material and of open-work character, and is preferably cotton knitted with open loops, so as to have considerable elasticity and to permit the free circulation of air through it; but braided fabrics of any suitable material may constitute the covering, provided that they possess the essentials of elasticity and openness.

45 The covering D is applied to the body B before the waistband is attached to the latter, and is fastened to said body at its ends by means of stitching through the tapes E E, which form the coverings for said ends and 50 the media for connection with said waistband,

said tapes being folded over the covering outside the ends of the latter, and held in place by stitching or other equivalent fastening; or any other suitable fastening for the cover may be employed.

55 The covering described prevents contact of the wire of the bustle when in use with adjacent garments, and so avoids the soiling of the latter by such contact. Said covering, being of an elastic nature, adapts itself to the contour 60 of the bustle, and does not interfere with the contraction or expansion, compression, or flexion of the latter, but, on the contrary, conforms to or follows the changes in shape of the body. Being open-work, it does not 65 impede the free circulation of air through the bustle-body, so that the latter remains, as heretofore, cool and healthful. The covering described improves the appearance of the article and enhances its attractiveness.

70 I have shown and described the covering as applied to a braided-wire bustle; but I do not confine my claim thereto, as the covering may be used on a bustle-body of woven wire or wire otherwise constructed or adapted to form 75 a bustle-body; nor is my improvement confined to a wire bustle, as the covering described may be applied to a bustle the body of which is material other than wire.

75 What I claim as my invention is—

1. The combination, with the body of a bustle made of braided or woven material, of a covering therefor of knitted, braided, or other elastic open-work textile material, substantially as shown and described.

80 2. The combination, with the body B of a bustle made of braided or woven material, of a covering, D, therefor, said covering being composed of knitted, braided, or elastic open-work textile material fastened to said body at 90 each end of the latter, substantially as shown and described.

85 3. The combination, with the waistband C and body B of a bustle made of braided or woven material and tapes E E, which form 95 end connections therefor, of an elastic open-work textile covering for said body, having its ends fastened to the ends of the latter beneath the tapes, substantially as shown and described.

4. The combination, with a braided body, B, of a bustle, of an elastic open-work covering therefor, substantially as shown and described.
5. The combination, with a bustle made of braided or woven material, the body of which is composed essentially or mainly of naked wire, of a textile elastic covering of braided, knitted, or equivalent open-work material, substantially as shown and described.

In testimony that I claim the foregoing I have hereunto set my hand this 28th day of October, 1886.

JOSEPH L. WELLS.
